[57] CLAIM

The ornamental design for a control unit housing for an electrical protection system, as shown and described.

DESCRIPTION

FIG. 1 is a plan view of a control unit housing for an electrical protection system embodying my design;
FIG. 2 is a front elevation of the housing of FIG. 1;
FIG. 3 is a side elevation as viewed from the left side of FIG. 2;

FIG. 4 is a side elevation as viewed from the right side of FIG. 2; and

FIG. 5 is a front perspective view of the housing of FIG. 1.

FIG. 1

FIG. 2

FIG. 4

FIG. 3
